CLAIM

The ornamental design for a grinding wheel mount, as shown and described.

DESCRIPTION

FIG. 1 is a side elevational view of a grinding wheel mount showing our new design, the side opposite being a mirror image;

FIG. 2 is a left end elevational view thereof;

FIG. 3 is a right end elevational view thereof;

FIG. 4 is a top plan view thereof, the bottom being a mirror image;

FIG. 5 is a longitudinal sectional view taken in the direction of the arrows on line 5—5 of FIG. 1.

The threads are shown symbolically to represent standard right-hand threads at the right-hand end of the mount and at the right-hand end of the shoulder screw, and fine, left-hand threads threadedly received in the middle portion of the mount.
